Inventor:

By Clarence O. Tracy
H. S. Bailey, Attorney.

UNITED STATES PATENT OFFICE.

CLARENCE O. TRACY, OF DENVER, COLORADO.

AUTOMATICALLY-OPERATING MOTOR-DRIVEN CARRIER.

1,351,930.

Specification of Letters Patent. Patented Sept. 7, 1920.

Application filed March 13, 1919. Serial No. 282,512.

To all whom it may concern:

Be it known that I, CLARENCE O. TRACY, a citizen of the United States of America, residing at the city and county of Denver 5 and State of Colorado, have invented a new and useful Automatically-Operating Motor-Driven Carrier, of which the following is a specification.

My invention relates to a new automatically operating motor-driven carrier, and the objects of my invention are:

First, to provide an automatically operating electric motor-driven carrier, that is arranged to be controlled by an operator 15 through an electric signal or an electric bell signaling system, or both.

Second, to provide an electric motor-driven carrier, that is automatically reversible, to move in the opposite direction to that 20 in which it is traveling.

Third, to provide an electric motor-driven carrier, that can be adapted to carry a large range of different kinds of merchandise, mail matter and other material from 25 terminal stations placed at any predetermined short or long distances apart.

Fourth, to provide an automatically operating electric motor-driven carrier, that is automatically controlled by a single operator 30 at one end of the carrying line, or, if desired, by an operator at each end of the carrying line, and

Fifth, to provide an automatically operating electric motor-driven carrier, mounted 35 on a trolley supporting wire, operatively connected to an electric current generating source, said carrier being arranged to support a motor, which receives current from a wire supported by said motor, and which is 40 also connected with the current generating source.

I attain these objects by the mechanism illustrated in the accompanying drawings, in which—

Figure 1 is a side elevation of the improved electric motor-driven carrier.

Fig. 2 is an end view of the same.

Fig. 3 is a diagrammatic view, illustrating the manner of closing a circuit as the carrier passes a station, to indicate the whereabouts of the said carrier, and also to break the circuit and stop the carrier at any desired station.

Fig. 4 is a front view of one of the brackets for supporting the feed wires.

Fig. 5 is a front view of the pivoted abut-

ment for changing the position of the gear carrying arm, which connects the motor with the gearing of the carrier.

Fig. 6 is a sectional view illustrating the 60 manner of forming the shifting lever in two sections, which are insulated one from the other.

Fig. 7 is a plan view illustrating the manner of locking the shifting lever in either 65 position, and

Fig. 8 is an end view illustrating a slight modification in the arrangement of the carrier.

Similar letters of reference refer to similar parts throughout the several views.

Referring to the drawings:

The principal views illustrated in Figs. 1, 2 and 3 embody the main features of my invention.

In these views, as well as in the remaining figures of the drawings, the numeral 1, designates the frame of the trolley, which preferably consists of side plates 2, positioned at predetermined distances apart by 75 spacing sleeves 3, through which cross bolts 4, pass, that are arranged to connect the side plates, as shown. This frame may be made of sheet metal plates and cross bolts, or it may be made in the form of a casting. I 80 mount between the sides of this frame, and at a short distance apart from each other, lengthwise of the frame, two trolley wheels or sheaves 5, each of which is provided with a V-shaped groove, in which the track wire 85 6, bears, and on which the trolley runs, as 90 will be hereinafter fully explained.

This track wire is supported upon brackets 7, which are secured to suitable standards or poles 7^A, which may be placed at any 95 desired distance apart from a few feet, in a store, to several hundred or several thousand feet, out of doors. For heavy material, suitably constructed supporting towers 100 may be used, such as when carrying ore, lumber, stone or other heavy materials, but poles or standards only are illustrated in the drawings. The sheaves are secured on shafts 8, that extend loosely through suitable bearings 9, that are formed in the side 105 plates of the trolley frame. These shafts and sheaves are arranged to be rotatively driven by the motor and they extend beyond one side of the trolley frame far enough to have gears 10 and 11, respectively, 110 mounted on them.

A pinion 12, meshes with the gear 11, and

this pinion is rigidly mounted on a shaft 13, rotatably mounted in the trolley frame. The upper edges of the plates 2, terminate in inwardly projecting flanges 14, upon which is bolted a block 15, of any suitable non-conducting material, such as a vegetable fiber, and this block extends the whole length of the plates. Through each end portion of this block extends one end of a 10 substantially semi-circular metal arm 16, and the other ends of these arms extend through a non-conducting block 17, similar to the block 15, and which is secured to the top of a box or receptacle 18, which is preferably made of metal, to afford the requisite strength and durability.

The arms 16, are formed with shoulders 19, which bear against the outer edges of the blocks 15 and 17 respectively, and the extremities of the arms 16, are threaded and receive nuts 20, which are screwed tightly against the adjacent edges of the blocks 15 and 17, and thus prevent a swinging movement of the box 18, and parts connected 25 therewith, with respect to the trolley frame.

The box is provided on one side and one end with hinged doors 21 and 22, respectively, which are normally held closed by spring catches 23.

30 Upon the bottom of this box is secured an electric motor 24, of any required power, and upon one end portion of the shaft 25, of this motor, is loosely mounted the lower end of an arm 26, which is made in two sections 35 which are separated by a short space, as shown, the sections being connected in the following manner: On each side of the opposing end portions of the two sections of the arm are placed strips 27, of insulating material, and upon these strips are placed metal strips 28, and these strips are tightly clamped against the arm sections by bolts or rivets 29, which pass through the non-conducting eyelets 30, in the arm sections, this 40 arrangement serving to insulate the arm sections from each other, so that currents from the motor cannot pass from the lower section into the upper section.

The upper end of the upper arm section is 50 formed with a bearing hub 31, in which is rotatably mounted a short shaft 32, on the inner end of which is rigidly secured a pinion 33, a sheave wheel 34, being rigidly secured on its outer end, which is connected 55 by any suitable flexible connection 35, with a similar sheave wheel 36, on the motor shaft 25, whereby the shaft 32, and its pinion 33, are rotated. The pinion 33, is rotated clockwise, and is adapted to mesh 60 either with the gear wheel 10, or the pinion 12, according to the position of the arm 26. Thus, when the pinion 33, is in mesh with the gear 10, the carrier is driven in the direction of the arrow, Fig. 1, and when the arm 65 is swung to cause the pinion 33, to engage

the pinion 12, the carrier is driven in the opposite direction.

The track or trolley wire 6, is connected at one end with a current source, and a second wire 37, also connected with the same current source as the track wire, is supported on the brackets 7, and also upon a grooved roller 38, which is mounted in a bearing bracket 39, which is secured upon an insulating medium 40, on the under side of the 75 motor. The terminal wires of the motor, or those connected with the field and armature, extend through the motor casing in the usual manner, and one of these wires 41, is electrically connected with the bracket 39, while the other terminal wire 42, is electrically connected with one of the side plates of the trolley. The current from the current source passes from wire 37, through bracket 39, and wire 40, to the motor, thence through 85 wire 42, to the trolley frame, and track wheels 5, and thence through track wire 6, to the current source, thus forming a circuit through the motor by which the same is operated, and the pinion 33, operated in the 90 manner previously described.

The system comprises an operating station, a terminal station, and as many intermediate stations as may be required, and the arm 26, is reversed, at the terminal station, to cause 95 the pinion 33 to disconnect from the gear wheel 10, and swing into mesh with the pinion wheel 12, and this reversing movement is accomplished in the following manner: The brackets which support the wires 6 and 37, are of the form shown most clearly in Fig. 2, comprising an upright portion which is secured to the pole, having a horizontal projection 43, adjacent its upper end, to which the track wire 6, is secured, and terminating at its lower end in a semi-circular bend 44, in which is supported the lower feed wire 37, this curved portion having a facing 45, of insulating material, upon which the wire 37, rests, and which prevents shunting 100 of the current through the bracket and into the pole. The last bracket of the series, or the bracket at the terminus of the line, is provided with a standard 46, which is bolted to the lower end of the bracket, as clearly 115 shown in Figs. 2 and 4. To the upper end of this standard is pivotally secured an abutment 47, of the form shown in Fig. 5, and comprising a hub, from which depend two legs 48, arranged at an acute angle to 120 each other, and upon the legs are slidably mounted weights 49, which are held in any required position on the legs, by set screws 50. An upwardly projecting finger 51, is pivotally secured to a lug 52, on the hub, in 125 such manner as to have a sidewise swinging movement in one direction only, and a spring 53, is secured to one leg of the abutment and bears against the finger, thereby to normally hold the same in a vertical position, and to 130

restore it to a vertical position when it has been turned to one side, in a manner to be presently described.

The trolley reversing arm 26, has a horizontally projecting tappet 54, which is adapted to strike the abutment finger 51, when the carrier arrives at the terminus of the line, and as the finger is arranged to swing in a counter direction to the approaching carrier, it receives the impact from the tappet, which causes the abutment to swing on its pivot, and thus permit the tappet to pass the finger. The degree of resistance offered by the abutment is determined by the position of the weights 49, it being apparent that when these weights are positioned as shown in Fig. 5, the abutment offers a greater resistance to the impact of the tappet, than would be the case if both weights occupied a position nearer the axis of the abutment or if the lower weight was raised to the position of the upper weight.

By this means the abutment can be arranged to offer the resistance necessary to throw the lever arm 26, and bring the pinion 33, in mesh with the pinion 12, thus reversing the direction of movement of the carrier.

The arm 26, is locked in either position, in the following manner: A guard 55, in the form of a metal strip, shaped as shown in Fig. 7, is secured at each end to the outer edge of the non-conducting block 17, so as to rest against the arm 26, and the arm has a spring 56, secured thereto, which bears against the block 17, and thus holds the arm 26, in engagement with the inner face of the guard 55. This face of the guard has two circular projections 57, and the arm is provided with a depression 58, adapted to receive either of the projections. Thus, when the arm is swung to the limit of its movement in either direction, it slides over the adjacent projection, until the said projection enters the depression in the arm, when the arm is forced out against the inner face of the guard and held upon the projection, which acts to lock the arm in this position until it is again reversed, as will be understood by reference to Fig. 7. When the tappet 54, strikes the finger 51, and reverses the arm 26, the said tappet swings the abutment on its pivot and passes the finger, as previously described, the current to the motor having been previously cut off, as will be presently described. The carrier is now at a standstill, and its contents may be removed, and other merchandise or packages may be placed in the box for the return trip. The carrier may be started on the return trip by signaling the operating station, in a manner to be presently described, and when the tappet 54, strikes the finger 51, the said finger will swing to one side and permit the

tappet to pass, without again reversing the arm.

The roller 38, which carries the feed wire 37, may be secured on one side of the motor, as shown in Fig. 8, and, thus arranged, the curved end of the bracket 7, may be dispensed with, which permits a hook 59, to be secured to the motor, upon which may be hung any article not adapted to be carried by the box 18.

As shown in Fig. 2, the bracket 7, is provided with a pivoted arm 60, the outer end of which is secured to the upper side of the wire 37, and this arrangement prevents swinging of the wire at each bracket, so that, as the carrier approaches a bracket, it will gradually cease swinging, and pass the bracket in a non-swinging or vertical position, which prevents its striking the bracket and the consequent injury to the bracket and carrier.

In the successful operation of the improved carrier, especially on long lines on which there are several intermediate stations, it is essential that the operating station be provided with a signaling system, by which an attendant may be notified of the arrival of the carrier at the various stations and at the terminus, and thus keep in touch with the movement of the car, as otherwise there would be no way of determining whether the carrier was moving forward, or whether it had come to a stop from any unknown cause.

In connection with the signaling system, it is also necessary that the movement of the carrier shall be controlled by the attendant, so that the carrier may be brought to a stop at any desired station, or at all of the stations, if necessary.

In accomplishing these ends, I employ an electrically operated signaling system, which I will now proceed to describe.

The operating station is provided with a switchboard 61, having switch levers 62 and 63, the switch 62, being arranged to control the trolley wire 6, while the switch 63 controls the feed wire 37. The cross arms 64, on the tops of the poles 7^A at the stations, are provided with contacts 65, 66 and 67, respectively (three stations being shown), which are connected by wires 68, 69 and 70, with lamps A, B and C, respectively, and the lamps are connected to a wire 71, which taps the feed wire 37.

A contact 72, is secured to the non-conducting block 15, on the trolley frame, and this contact is electrically connected with one of the side plates of the trolley frame, by a wire 73. The contact 72, is in position to engage the contacts 65, 66 and 67, and as each station contact is engaged by the trolley contact 72, a circuit is closed through the corresponding lamp, which is thereby lighted, thus indicating the station passed.

by the carrier. In addition to the lamps, a bell 74, is arranged in the lamp circuit, the bell being connected to a transformer 75, one terminal of which connects with the wire 37, while the other terminal connects with lamp circuit wires. Thus, when a circuit is closed through any one of the lamps, the circuit through the bell is also closed, and the bell rings, thereby notifying the attendant, by both the lamp and bell, that the carrier has passed the station indicated.

In addition to the above described signaling system, I provide means for breaking the circuit through the motor, at any desired station, so that the carrier may be stopped and the fact indicated at the operating station.

To accomplish this, I connect to the lamp wires 68, 69 and 70, wires D, E and F, respectively, and the opposite ends of the wires are provided with contacts X, Y and Z, respectively, as shown. A switch 76, is arranged to engage any one of the contacts X, Y or Z, and this switch is connected by a wire 77, with one pole of a battery 78, the other pole of which is connected by a wire 79, with one of the terminal wires of a magnet, the other terminal wire of which is connected by a wire 80, with the feed wire 6. An armature 81, is operatively positioned with respect to the magnet, and this armature is provided with circuit closers 82, and 83, on opposite sides of the same, the closer 82, being insulated from the armature, and being adapted to make or break a circuit through the wire 37, which for this purpose has a gap opposite the closer 82, the adjacent ends of the wire being provided with contacts 84, which are normally engaged by the closer 82, thereby permitting current to pass through the said wire. The closer 83, on the armature stands opposite and adjacent to a pair of contacts 85, one of which connects by a wire 86, with the wire 79, leading from the battery to the magnet, and the other connects by a wire 87, with one of the terminals of a bell 88, the other bell terminal being connected with the wire 77, which connects the battery with the switch 76.

It will thus be seen that when the switch 76, is out of engagement with any of the contacts X, Y or Z, the carrier will pass the several stations without stopping, but when the switch 76 is turned to engage any one of the contacts X, Y or Z, a circuit is formed through the battery and magnet, and the armature 81, is attracted by the magnet, thereby breaking the circuit through the feed wire 37, and closing a circuit through the battery 78, and bell 88, as follows: In Fig. 3 the switch 76, is shown engaging the contact X, of wire D, which taps the lamp circuit wire 68, which connects with the contact 65, at the last station. When the car-

rier reaches this station its contact 72, engages the contact 65, and current passes through wires 68, D, switch 76 and wire 77, to battery 78, thence through wire 79, to magnet, and from the magnet through wire 80, to the feed wire 6, thus making a circuit through the battery and magnet. The magnet is thereby energized, and attracts the armature, which thus breaks the circuit through the feed wire 37, and closes a circuit through the battery 78, and also through the bell 88, by the engagement of the armature circuit closer 83, with the contacts 85. The breaking of the circuit through the wire 37, by the armature 81, cuts off the current to the motor, but it is carried forward by its momentum until its tappet 54, strikes the finger 51, of the abutment and reverses the arm 26, as previously described.

When the armature 81, is attracted by the magnet, it is caught by a dog 89, and held in this position, thus preventing the closing of the circuit through the motor, but the bells continue to ring and the lamp remains on, until the tappet 54, strikes the finger 51, when the carrier contact passes off from a wire 90, which extends from the last station contact 65, and terminates above where the tappet strikes the abutment, thus breaking the circuit through the battery and the bell 74.

The operating station is notified that the carrier is ready to be returned, in the following manner: A wire 91, is connected to the track wire-holding arm 60, which is hinged to the bracket 7, and this wire 91, connects with a contact 94; a wire 93, connects at one end to the wire 6, and at its other end with a contact 92, adjacent to contact 94. A switch or push button 95, is arranged to engage the two contacts, and this closes a circuit through the lamp A, bell 74, and battery, the current passing through track wire 6 to wire 93, and contacts 92 and 94, to wire 91, thence through wire 37, and lamp wire 68, to the wire D, through switch 76, wire 77, and battery, and thence through the magnet and wire 80, to track wire 6, thus completing the circuit. When the attendant at the operating station is notified in this manner that the carrier is ready for the return trip, he moves the switch 76, off the contact X, and lifts the dog 89, which permits the armature 81, to assume its normal position, thereby closing the circuit through the feed wire 37, and the arm 26, having been reversed as previously described, the carrier returns to the operating station, signaling for each intermediate station as it passes.

A lamp 96, is mounted on one of the arms 16, of the carrier, and one of its terminals is connected by a wire 97, with the trolley frame, and its other terminal is connected

by a wire 98, with one pole of a switch 99, secured on the carrier box 18, and the other pole of the switch is connected by a wire 100, with the bracket 39, of the feed wire, 5 supporting wheel 38. The switch 99, is adapted to cut the lamp 96, out of the circuit during the day, and to close a circuit through the said lamp after dark. The signaling wires 68, 69 and 70, are supported 10 in rings 101, formed in the upper ends of the bracket 7.

Having described my invention, what I claim as new and desire to secure by Letters Patent, is:

15 1. In an electrically operated carrier of the character described, the combination with current feed wires, one of which is a track wire, of a trolley on the track wire whose wheel shafts have gear wheels there- 20 on, a pinion in mesh with one of said gear wheels, a parcel carrier and a motor suspended from said trolley, a bracket secured to, but insulated from said motor, having a sheave wheel for supporting the other feed 25 wire, the motor terminals being connected, respectively, with the trolley and with the sheave wheel bracket, an arm loosely mount- 30 ed at one end on the motor shaft, and hav- 35 ing a spindle rotatably mounted in its op- posite end, a gear rigidly mounted on one end of the spindle and adapted to mesh with one of the trolley shaft gear wheels, or with the pinion which meshes with the other gear wheel, a wheel on the other end 40 of the spindle, a wheel on the motor shaft, and an endless flexible connection connect- 45 ing the two wheels, means for automatically shifting the arm to throw the pinion out of gear with one wheel and into gear with the 50 other wheel, and means for holding the arm in either position.

2. In an electrically operated carrier of the character described, the combination with current feed wires, one of which is a track wire, of a trolley on the track wire, a parcel carrier and a motor suspended from 55 said trolley, a bracket secured to, but insulated from the motor having a sheave wheel for supporting the other feed wire, the motor terminals being connected respectively with the said bracket and with the trolley, gear wheels on the trolley wheel shafts, a pinion in mesh with one of the gear wheels, an arm loosely mounted at one end on the 60 motor shaft, a spindle loosely mounted in the other end of the arm having a pinion on one end adapted to mesh with one of the gears on the trolley wheel shafts, or with the pinion in mesh with the other gear, a 65 belt wheel on the other end of the spindle, a belt wheel in the motor shaft, and a belt connecting said wheels, an abutment at one end of the line with which the said arm engages to shift the same, and disconnect its pinion from one gear, and connect it with

the other gear, and catches for holding said arm in either position, said arm being formed in two sections, which are insulated from each other.

3. In an electrically operated carrier of the character described, the combination with a trolley having gears on its wheel shafts, a pinion in mesh with one of said gears, a parcel carrier supported by the trolley, a motor supported on the parcel carrier, and feed wires in circuit with said motor, one of which supports said trolley, of an arm loosely mounted on the motor shaft having a pinion on its upper end adapted to mesh with one of the trolley shaft 75 gears, or the pinion which meshes with the other gear, a guard secured to the carrier and adapted to bear against and confine the arm, said arm having a depression, projections on said guard, said depression being 80 adapted to receive one or the other of said projections and thus hold the arm in either of two positions, a spring for holding said arm in contact with said guard, and an abutment at the end of the trolley line which is 85 engaged by said arm, whereby the arm is 90 shifted.

4. In an electrically operated carrier of the character described, the combination with a series of poles, brackets secured 95 thereon, and current feed wires supported on said brackets, one of which is a track wire, of a trolley on said track wire having a parcel carrier and a motor attached thereto, said motor being in circuit with said feed 100 wires, operating gears on the trolley, a pinion in mesh with one of said gears, an arm loosely mounted on the motor shaft, and a pinion on said arm, driven by said motor, and adapted to engage one of the trolley 105 shaft gears, or the pinion which meshes with the other gear, a pivoted abutment on the last bracket of the series for engaging and shifting the position of said arm, and means for varying the resistance offered by said 110 abutment.

5. In an electrically operated carrier of the character described, the combination with a series of poles having brackets thereon, and current feed wires supported on said 115 brackets, one of which is a track wire, of a trolley on said track wire having a parcel carrier and a motor attached thereto, said motor being in operative circuit with the feed wires, operating gears on the trolley, a 120 gear in mesh with one of said operating gears, an arm loosely mounted on the motor shaft, a pinion on said arm driven by said motor and adapted to mesh with the latter gear or with the other trolley operating 125 gear, a tappet on the said arm, a pivotally mounted abutment on a fixed support at the end of the trolley line, for engaging said tappet, to move the arm to reverse position, said abutment comprising a hub, a tappet 130

engaging finger projecting therefrom, and depending legs, and adjustable weights on said legs.

6. In an electrically operated carrier of
5 the character described, the combination
with a trolley line comprising a series of
poles having brackets thereon, current feed
wires on said brackets, one of which is a
10 track wire, a carrier and a motor supported
by the trolley, said motor being in operative
circuit with the feed wires, operating gears
on said trolley, a gear in mesh with one of
15 said operating gears, a swinging member
having a pinion thereon, driven by the
motor, for engaging the latter gear or the
other operating gear, a fixed member at one
end of the line, a pivoted abutment on said
fixed member, comprising a hub, a finger

projecting therefrom and hinged to swing
in a counter direction to the approaching 20
trolley, a spring for normally maintaining
the finger in a vertical position, legs depend-
ing from the hub, and weights adjustably
mounted on said legs, said abutment being
adapted to engage the swinging member 25
and shift the same, to disengage its pinion
from one trolley operating gear; and engage
the gear in mesh with the other operating
gear.

In testimony whereof I affix my signature 30
in presence of two witnesses.

CLARENCE O. TRACY.
